United States Patent Office

Des. 217,731
Patented June 2, 1970

217,731

CLOCK

Robert O. Ernest, Oak Park, Ill., assignor to Sunbeam Corporation, Chicago, Ill., a corporation of Illinois

Filed June 30, 1969, Ser. No. 17,980

Term of patent 14 years

Int. Cl. D10—01

U.S. Cl. D42—7

Fig. 1.

Fig. 2.

Fig. 3.

Fig. 4.

Fig. 5.

FIG. 1 is a front elevational view of a clock showing my new design;

FIG. 2 is a top plan view thereof;

FIG. 3 is a side elevational view thereof when viewed from the right-hand side of FIG. 1;

FIG. 4 is a side elevational view thereof when viewed from the left-hand side of FIG. 1; and

FIG. 5 is a sectional view thereof taken along the section line 5—5 of FIG. 1.

I claim:

The ornamental design for a clock, as shown.
